M. BROCK

POWDER PUFF

Filed Jan. 26, 1923

Inventor:

Max Brock

By his attorney, Joseph R. Long

UNITED STATES PATENT OFFICE.

MAX BROCK, OF NEW YORK, N. Y., ASSIGNOR TO I. B. KLEINERT RUBBER COMPANY, OF NEW YORK, N. Y., A CORPORATION OF NEW YORK.

POWDER PUFF.

Application filed January 26, 1923. Serial No. 614,972.

To all whom it may concern:

Be it known that I, MAX BROCK, a citizen of the United States, and a resident of the city, county, and State of New York, have 5 invented a certain new and useful Improvement in Powder Puffs, of which the following is a specification.

This invention relates to an improvement in a powder puff combined with a holder or 10 cover for the same which retains the same in a compact condition with the powder-applying portions of the puff held in such position that the possibility of the same becoming soiled readily is avoided.

15 A further object of this invention is to provide a powder puff having several powder-receiving and applying surfaces so that several kinds of powder may be applied from the one puff and to provide a cover 20 or casing for said puff which will retain said powder-applying surfaces in a covered condition when the same are not in use.

With these objects, and other objects 25 which may hereinafter appear, in view, I have devised the particular arrangement of parts hereinafter set forth and more particularly pointed out in the claims appended hereto.

Reference is to be had to the accompanying 30 drawing, forming a part hereof in which—

Figure 1 is a plan view of my improved powder puff and its cover.

Figure 2 is a rear view, or a view of the underside of the puff and casing.

35 Figure 3 is a sectional view on the line 3—3 of Figure 1, looking in the direction of the arrows.

Figure 4 is a plan view of the powder puff removed from the casing, with a portion 40 being broken away to disclose construction.

Figure 5 is a sectional view on the line 5—5 of Figure 4 looking in the direction of the arrows, and

45 Figure 6 is a plan view of a modified form of construction.

Throughout the various views of the drawings, similar reference characters designate similar parts.

The puff 1 is composed of two folded 50 powder-applying sections 2 and 3 which are preferably formed of some absorbent pile fabric or the like to receive and retain the powder. These sections 2 and 3 are arranged to be spread out flat when the pow-

der is to be applied. As there are two of 55 these sections, it will be apparent that two different kinds of powder may be applied from the same puff.

The folded sections 2 and 3 are covered by suitable backing strips 4 and 5 which 60 are secured to them by stitches 6 extending about their edges.

At 7 is a section or disk of material forming the cover for the puff which is preferably of greater diameter or area than the 65 puff and is secured on one side of the same.

At 8 is a tape or ribbon through which the hand of the user may be inserted in using the puff. The edge of the cover or disk 7 is suitably reinforced by merrow 70 stitching 9. The puff is secured to the section or disk 7 by means of stitches 10 located at opposite points and which extend through the puff, tape and the cover member 7.

At 11 and 12 is a pair of spaced-apart straps which extend parallel to one another and across the face of the cover portion 7. Each of these straps is intended to overlie one-half of the puff and retain the same 80 down flat upon the back member 7 so that the powder-applying surfaces 2 and 3 are retained in their folded condition when the puff is not in use.

To use the puff, the section to be used is 85 removed from beneath its strap 11 or 12 as the case may be and it is spread out flat and the powder applied.

It will be noted that the securing stitches 10 extend at a point intermediate of the 90 folds in the powder-applying section so that they do not pass through the same.

It is also to be noted that the ends of the straps 11 and 12 are secured to the back member 7 by means of the merrow stitches 9 95 which form the reinforce or binding for the edge of the back member or cover 7.

It is preferable to form the cover out of some easily washable material such as thin sheet rubber or the like and thus parts of the 100 puff not used for the application of the powder may be constructed of similar material, is desired.

In Figure 6, a modified form of construction is provided wherein all the parts of the 105 article are similar to that disclosed in Figure 1 with the exception of the fact that straps 13 and 14 are shown provided with

suitable reinforcing means in the nature of merrow stitching 15 extending along their longitudinal edges, such reinforcement acting to prevent tearing of the straps when they are temporarily distorted to remove portions of the puff located below them.

From the foregoing, it is obvious that my invention is not to be restricted to the exact embodiment shown but is broad enough to 10 cover all structures coming within the scope of the annexed claims.

Having described my invention, what I claim is:

1. An article of the class described, comprising a powder puff having a pair of powder-applying faces, a section of material secured to said puff and spaced-apart straps extending across one face of said section and adapted to overlie said powder-applying sec-

tions and maintain the same in a folded condition. 20

2. An article of the class described comprising a powder puff, a flexible disk on which said puff is adapted to be secured and spaced-apart parallel straps extending 25 across the face of said disk and adapted to maintain the puff flat upon said disk.

3. An article of the class described, comprising a powder puff having a pair of powder-applying surfaces, a cover attached to 30 said puff comprising a section of material of greater area than said puff secured on one side thereof and having a pair of spaced-apart flat parallel straps extending across said puff on the opposite side thereof. 35

Signed at the city, county and State of New York, this 8th day of January, 1923.

MAX BROCK.
